R. B. PUCKETT & H. R. ABBOTT.
METHOD OF CUTTING LIFTS FROM THE HEEL SEAT PORTION OF OUTER SOLES.
APPLICATION FILED APR. 17, 1916.

1,202,423.

Patented Oct. 24, 1916.

UNITED STATES PATENT OFFICE.

ROBERT B. PUCKETT AND HARRY R. ABBOTT, OF ST. LOUIS, MISSOURI.

METHOD OF CUTTING LIFTS FROM THE HEEL-SEAT PORTION OF OUTER-SOLES.

1,202,423.

Specification of Letters Patent. Patented Oct. 24, 1916.

Application filed April 17, 1916. Serial No. 91,742.

To all whom it may concern:

Be it known that we, ROBERT B. PUCKETT and HARRY R. ABBOTT, citizens of the United States, residing in the city of St. Louis and 5 State of Missouri, have invented new and useful Improvements in Methods of Cutting Lifts from the Heel-Seat Portion of Outer-Soles, of which the following is a specification.

10 This invention relates to the art of manufacturing shoes, and has special reference to a novel method of removing a lift from the heel-seat portion of the outer sole.

In the manufacture of shoes as now practised, the outer sole, consisting of an integral piece of leather, is secured to the upper and then the heel secured to the heel-seat portion of the sole. The heel-seat portion of the sole is never subjected to any 15 wear, and it has heretofore been proposed to remove a portion of this leather in the shape of a lift which may be used as the top lift for a heel, and thereby secure great economy in the manufacture of shoes. In 20 attempting to do this the lift has been cut from the heel-seat portion of the outer sole, and a filling tenon of approximately the size of the lift cut, and of cheaper material, has been secured to the heel and then the heel applied in position in the usual way after the 25 sole has been secured to the shoe, so that the tenon will fill the space made by removing the lift. It was soon discovered that this was an impracticable method of 30 procedure, owing to the impossibility of properly positioning the recess in the sole with respect to the tenon on the heel, so that when the heel was applied it would be exactly 35 centered with respect to the sole.

40 In a companion application of the present inventors, filed January 12th, 1916, Ser. No. 71,619, it has been proposed to cut the lift from the sole after the tread portion of the sole has been sewed to the upper, and before the heel-seat portion has been nailed thereto. In carrying out this idea it was 45 thought possible to cut the lift from the sole by the use of a reciprocating die while the last was yet in the upper, thus utilizing the last to offer the necessary resistance to the die to enable the latter to cut through the sole. It was found, however, that the ordinary lasts used are not uniform in size, even 50 for the same style of shoe, and that frequently the die would cut through the outer 55

sole and into the inner sole, and such method of procedure was found impracticable.

The present invention is concerned with a novel method whereby the idea of cutting the lift from the sole after it has been secured to the upper may be carried out in a simple, efficient and economical manner.

Referring now to the drawing—Figure 1 is a plan view showing a shoe with the outer sole secured thereto, and in position on a 60 novel support permitting a lift to be cut from the heel-seat portion without the danger of cutting any other portion of the shoe, the view showing the sole with the cut lift removed; Fig. 2 is a view in side elevation, showing a shoe in position on the improved support, and illustrating conventionally a die for cutting the lift from the heel-seat portion of the sole; Fig. 3 is a view in front elevation of the improved support; and Fig. 4 is a sectional view of a heel supplied with a tenon for filling the opening made by removing the lift from the outer sole.

The present invention, of course, is not concerned with the particular apparatus shown, but the same has been found to be a very useful and convenient means of carrying out the invention, and said apparatus forms the subject-matter of a separate application for patent.

80 A brief description of the apparatus will therefore be given.

The numeral 1 indicates a support, such as a table, or the like, on which is mounted a 85 head 2 having yoke-members 3, which are connected at their upper end by a block 4, which is preferably cast integral with the yoke-members 3. The block 4 is flat on its upper side, and has a rounded end portion 90 5 projecting slightly beyond the front side of the yoke-members 3, and its under side is inclined rearwardly from said front end to the end of an extension 6 which projects a considerable distance beyond the rear sides of the yoke-members 3. The extension 6 is in the form of a plate, and at the point where it projects from the block 4 the latter provides a vertically-disposed shoulder 7. Secured on the upper side of the block 4 is 95 a flat, metal plate 8 which at its rear side is bent at right angles to itself, as indicated at 9, to extend over the shoulder 7, to which it is secured by means of screws 10. The under side of the block 4 and of the plate 100 6 form one continuous inclined surface, as 105 110

shown more clearly in Figs. 2 and 3, and indicated by the numeral 11. The numeral 12 indicates a gage-plate which is cut away to provide a V-shaped recess from the edges 5 of which depend guide-members 13 formed integral with said plate and converging from the forward edge and outer side thereof to a point about midway of the plate. Toward its outer end the plate 12 is provided with slots 14 which are adapted to loosely receive the screw-threaded ends of set screws 15 which pass through apertures 16 formed in the rear end of the plate 6, the screw-threaded ends of said screws being received in screw-threaded apertures formed in the ends of a nut plate 17.

In proceeding according to the present invention, an outer sole 18 is stitched to the upper in the usual way, as indicated by the 20 row of stitching 19, leaving a heel-seat portion 20 free, that is, unconnected with the upper. The operator places this heel-seat portion on the plate 8 and places the shoe between the yoke-members 3, its heel-portion 25 engaging the inclined side 11 of the block 4, and being guided to a true central position by the guide-members 13, which also act to limit the inward movement of the shoe. A die 21, which is shown removably 30 secured in a holder 22, is then reciprocated in a defined path, as by a plunger 22^a, in any preferred way to cut a lift from the heel-seat portion 20, in which operation the cutting edge of the die will pass through the 35 outer sole and engage the plate 8 which is preferably of soft metal. The cutting of the lift provides an opening 23 in the heel-seat portion of the sole, which is correctly positioned with reference to the heel portion 40 of the shoe. When the shoe is removed from the block 4 the lift is carried with it and is then easily removed by hand. The heel-seat portion of the outer sole is then nailed to the counter and inner sole of the 45 upper in the usual way, after which a heel 24, provided with a tenon 25, is applied to the outer sole, the tenon filling the opening 23 made by removing the lift from the sole. By loosening the set screws 15 it is obvious 50 that the gage-plate 12 may be adjusted to permit the guide-members 13 to properly position varying sizes of shoes.

By proceeding according to the method

outlined above, it will be seen that a lift may be cut from an outer sole in such manner that when the heel having a filling tenon thereon is applied to the sole the heel will be correctly positioned or centered on the latter. 55

A machine which may be advantageously used for practising the above method, but 60 which, apart from the mechanism or support herein illustrated, is not of the invention of the present applicants, forms the subject-matter of a separate application by other parties. 65

We claim:

1. In the manufacture of shoes, the method which consists in securing the tread portion of an outer sole to the upper, separating the heel-seat portion of the sole from the heel 70 portion of the upper, and then cutting a lift from the heel-seat portion of the sole while thus separated from the upper.

2. In the manufacture of shoes, the method which consists in securing the tread portion 75 of an outer sole to the upper, interposing a support between the heel-seat portion of the sole and the heel portion of the upper, and then cutting a lift from said heel-seat portion by producing relative movement between said support and a cutting die. 80

3. In the manufacture of shoes, the method which consists in securing the tread portion of an outer sole to the upper, inserting a support having diverging faces between the 85 heel portion of the upper and the heel-seat portion of the outer sole, whereby to separate said portions of the shoe, and then cutting a lift from the heel-seat portion of the sole while the latter is maintained separated 90 from the upper.

4. In the manufacture of shoes, the method which consists in securing the tread portion of an outer sole to an upper, placing the shoe in a defined position on a support with 95 the support inserted between the heel-seat portion of the sole and the heel portion of the upper, and cutting a lift from the heel-seat portion of the sole by reciprocating a die in a defined path relative to said support, 100 and into contact therewith.

In testimony whereof, we have hereunto set our hands.

ROBERT B. PUCKETT.
HARRY R. ABBOTT.
